UNITED STATES PATENT OFFICE.

DANIEL I. REITER, OF NEW YORK, N. Y., ASSIGNOR TO RAU FASTENER CO. INC., OF PROVIDENCE, RHODE ISLAND, A CORPORATION OF RHODE ISLAND.

BAG LOCK.

Application filed August 2, 1927. Serial No. 210,180.

This invention relates to the class of devices such as latches or buckle clasps for locking the closing flaps of articles such as hand bags, pocketbooks, brief cases, etc.

Some of the objects of the present invention are: to produce a more efficient and effectual device of the character mentioned; to facilitate the application of the co-operating parts of the device for use, and to produce a locking device or buckle clasp which can be conveniently manipulated in carrying out the locking and unlocking operations.

With the foregoing, other objects of the invention will appear when the following specification is read in conjunction with the accompanying drawings, in which—

Figure 1 is an elevation of a hand bag with the device of the present invention applied thereto.

Fig. 2 is a sectional view taken on the line 2—2 of Fig. 1 and drawn on an enlarged scale.

Fig. 3 is an elevation of the hasp.

Fig. 4 is a sectional view taken on the line 4—4 of Fig. 3.

Fig. 5 is a sectional view taken on the line 5—5 of Fig. 3.

Fig. 6 is an elevation of the latch unit.

Fig. 7 is a sectional view taken on the line 7—7 of Fig. 6.

Fig. 8 is a sectional view taken on the line 8—8 of Fig. 6.

Figs. 9 and 10 are views illustrating a modified form of buckle clasp.

The device of the present invention consists essentially of two elements, an element 10 and an element 11 which are employed respectively, when the device is in actual use, on the closing flap and receptacle-body of a hand bag or the like such as the one appearing in Fig. 1, in which the bag B is provided with a closing flap F connected to or attached in any suitable manner to a portion of the receptacle body R. The two elements 10 and 11 cooperate to releasably hold the closing flap in a closed position, and to permit the closing flap to be swung to an open position.

Referring now more particularly to Figs. 3, 4 and 5 it will be apparent that, the element 10 is in the nature of a hasp and is stamped, bent and formed of a single piece of material, either base or precious metal to provide a plate 12 having an opening 13 therein, an offset portion 14 which affords a recess 15, and attaching prongs 16. The element or

hasp 10 is attached to the closing flap by causing the prongs 16 to impale the same, whereupon the said prongs are bent to be disposed behind the offset 14 to cause the material of the flap to enter the recess 15 and thereby effect a practical and adequate attachment of the element.

Referring now to Figs. 6, 7 and 8, it will be apparent that the element 11 comprises a mounting 17, a latch lever 18, and a flexible member 19. The mounting 17 is stamped, bent and formed from a single piece of material such as base or precious metal of the kind from which the element 10 is made, to provide a plate or body portion 20 having an opening 21 therein near the top end thereof, recesses 22 opening to said opening 21, flanges 23, and prongs 24. The latch lever 18 is substantially S-shaped and is provided near one end thereof with axially aligned pintles 25 and an extremity 26 beyond the pintles 25. The latch lever 18 is associated with the mounting 17 by extending the same through the opening 21 to bring the pintles 25 respectively in the recesses 22. The member 19 is then arranged adjacent the plate 20 between the same and the flanges 23. The flanges and the prongs 24, each of which are bent substantially at a right angle with respect to the plate 20, serve to confine or retain the member 19 in place. The member 19 serves to confine the pintles 25 in the recesses 22. A portion of the member 19 also coacts with the extremity 26 to hold the latch lever either in the locking position as shown in Fig. 7 or in the open position as shown in dotted lines in Fig. 7. Therefore, when the element 11 is attached to a portion of the body R by causing the impalement of the prongs 24 through said portion and by bending the said prongs as shown in Fig. 2, the element 11 will be held for cooperation with the element 10.

From the foregoing it will be apparent that, when it is desired to swing the flap F to an open position, the latch lever 18 will be swung by taking hold of the free extremity and swinging outwardly and upwardly thereon. This swinging of the latch lever 18 will cause the extremity 26 to flex a portion of the member 19 and when the said extremity has been moved below the plane of the axis of the pintles 25, that portion of the member 19 which has been flexed will return to a normal condition and hold the latch lever in an open

position. When the latch lever is in an open position the hasp may be readily slid off of the same to permit the flap to be swung open. When it is desired to lock the flap F in a closed position it is necessary to bring the flap down so that the hasp may be slid over the latch lever 18, whereupon the free end of the latch lever is pressed downwardly to the position shown in Figs. 2 and 7, in which 10 position a portion of the flexible member 19 acts to prevent the latch lever from having movement since it is disposed across the arc described by the extremity 26.

Figs. 9 and 10 illustrate a type of latch 15 which is conventional except that I have eliminated the use of the usual holes through which rivets are passed, and have substituted a pair of prongs 50 which eliminate the riveting operation and materially simplify the 20 construction of the device.

I claim:

1. A latch unit comprising a mounting stamped, bent and formed from a single piece 25 of material to provide a plate having an opening therein, recesses in the plate, attaching prongs on the plate for engagement with a support, and flanges on the plate; a latch lever extending through the opening in said

plate and having pintles which are disposed in said recesses; and a flexible member held in place by said prongs and flanges and serving to confine said pintles in said recesses to complete the pivotal connection of the latch lever to the mounting; said latch lever having an extremity beyond the pintles which coacts with said flexible member to releasably hold the latch lever in different positions. 30

2. In a device of the character described, a mounting including flanges and prongs, a latch pivotally carried by said mounting, and flexible means on said mounting retained by said flanges and said prongs which coacts with means on said latch for releasably holding the latch in adjusted position. 35

3. A latch unit comprising a mounting stamped, bent and formed from a single piece 40 of material, recesses formed in said mounting adapted to receive the pintles of a pivoted latch member, and flexible means associated with said body for retaining said pintles within said recesses, said means being adapted to retain the latch in adjusted position, said means being retained adjacent said pintles by the provision of flanges and prongs 45 associated with said mounting.

DANIEL I. REITER.
